UNITED STATES PATENT OFFICE

129,634

DESIGN FOR A GENERATOR FOR PRODUCING RADIUM ACTIVITY

Sally C. Bryan, Denver, Colo.

Application May 5, 1941, Serial No. 100,795

Term of patent 14 years

to all whom it may concern:

Be it known that I, Sally C. Bryan, a citizen of the United States, residing at Denver, in the County of Denver, State of Colorado, have invented a new, original, and ornamental Design for a Generator for Producing Radium Activity, of which the following is a specification, reference being had to the accompanying drawing, forming a part thereof.

Fig. 1 is a top plan view of a generator for producing radium activity, showing my new design.

Fig. 2 is an elevational view of the unit, showing my new design.

I claim:

The ornamental design for a generator for producing radium activity, as shown.

SALLY C. BRYAN.
